US00D833462S

(12) **United States Design Patent** (10) **Patent No.:** **US D833,462 S**
Dahlen (45) **Date of Patent:** **** Nov. 13, 2018**

(54) **DISPLAY SCREEN WITH GRAPHICAL USER INTERFACE FOR A COMMUNICATION TERMINAL**

(71) Applicant: **KENALL MANUFACTURING COMPANY**, Kenosha, WI (US)

(72) Inventor: **Kevin Dahlen**, Lindenhurst, IL (US)

(73) Assignee: **KENALL MANUFACTURING COMPANY**, Kenosha, WI (US)

(**) Term: **15 Years**

(21) Appl. No.: **29/618,699**

(22) Filed: **Sep. 22, 2017**

(57) **CLAIM**

The ornamental design for a display screen with graphical user interface for a communication terminal, as shown and described.

DESCRIPTION

The FIGURE is a front view of a display screen with graphical user interface for a communication terminal.

The broken lines showing the display screen, text, and portions of the graphical user interface form no part of the claimed design.
